HOLE SPOTTER

Herman J. Schorle, Astoria, Long Island, N. Y., assignor to Worthington Pump and Machinery Corporation, Harrison, N. J., a corporation of Delaware

Application March 21, 1938, Serial No. 197,295

2 Claims. (Cl. 255—45)

This invention relates to rock drilling equipment, and more particularly to a hole spotter for holding and guiding drill steels during the starting of a drill hole.

An object of the invention is to provide a hole spotter which is a unitary structure and may be attached to conventional types of rock drilling machines such as those shown in Patents Numbers 914,737, 1,690,859, and 709,022, and which can be quickly and easily moved into drill steel holding and guiding position or moved out of drill steel holding and guiding position and clear of the drill steel so as not to interfere with the continued operation of the drilling machine after the hole has been started.

With these and other objects in view, as may appear from the accompanying specification, the invention consists of various features of construction and combination of parts, which will be first described in connection with the accompanying drawings, showing a hole spotter of the preferred form embodying the invention, and the features forming the invention will be specifically pointed out in the claims.

In the drawings:

Figure 1 is a view partly in section and partly in side elevation showing the improved hole spotter in drill steel guiding position.

Figure 2 is a view similar to Figure 1 showing the improved hole spotter out of drill steel guiding position.

Figure 3 is a fragmentary end view of the hole spotter.

Figure 4 is a detail cross section taken on the line 4—4 of Figure 1.

Figure 5 is an end view of a plunger embodied in the hole spotter structure.

Referring more particularly to the drawings, the improved hole spotter comprises an attaching bracket 1 which may be attached in any suitable manner to the frame A of a rock drilling machine. However, in the drawings the bracket 1 is shown as attached to the end of the feed screw B of a rock drilling machine of approved construction such as the one shown in Patent 914,737.

The attaching bracket 1 has a cylinder 2 formed thereon in which is slidably mounted a plunger 3. The plunger 3 has a stem 4 formed thereon and projecting through the rear end 5 of the cylinder 2. A spring 6 is mounted about the stem 4 and engages between the end 5 of the cylinder 2 and the collar 7 carried by the stem 4 for urging the plunger 3 rearwardly in the cylinder 2. The forward end of the plunger 3

is provided with a longitudinally extending slot 8 opening out through its forward end in which fits the flattened end 9 of the carrying standard 10.

The carrying standard 10 is pivotally connected to the plunger 3 by means of the pivot pin 11 and it has its lower or inner end 12 rounded as clearly shown in Figures 1 and 2 of the drawings for riding over the inner end 13 of the slot 8 during the movement of the carrying standard 10 from its drill steel guiding position into its non-active position.

The carrying standard 10 has its upper or forward position 15 cylindrical in shape and this cylindrical portion 15 rotatably receives a stem 16 on the upper end of which are formed the drill steel guiding members 17 and 18.

The drill steel guiding members 17 and 18 are similar in construction to the drill steel guiding members 7 and 8 of my companion application filed of even date herewith and the stem 16 has a flat side 19 which cooperates with a moving locking handle 20. The moving locking handle 20 cooperates with the way 21 formed on the carrying standard 10 and its construction as well as the construction of the way 21 and their cooperation is the same as the construction and operation of the corresponding parts in my companion application above mentioned.

The carrying standard 10 has a pair of cams 22 formed at the lower end of its cylindrical portion 15 and these cams ride over the cam surfaces 23 formed on the forward end of the cylinder 2 during the pivotal movement of the carrying standard 10 on its pivot 11 for moving the plunger 3 forwardly and outwardly in the cylinder 2 against the tension of the spring 6 so as to permit the carrying standard 10 to be moved from its vertical active position as shown in Figure 1 of the drawings into its horizontal inactive position as shown in Figure 2. The narrow flat end 9 of the carrying standard 10 is of such width that when the carrying standard is moved into its horizontal inactive position the end portion of the end 9 will extend into the slot 8 in the plunger 3 and into the forward end of the cylinder 2 providing stabilizing means for holding the standard 10 quiet during the drilling operation of the drilling machine with which the hole spotter is exhausted.

As previously pointed out, the construction and operation of the drill steel guiding members 17 and 18 is the same as that of the corresponding drill steel guiding members in my companion application and therefore when it is desired to

steady a drill steel as shown at C during the starting of a drill hole, the stem 16 is rotated to bring the members 17 and 18 into the position shown in both solid and dotted lines in Figure 2 of the drawings, at which time they will clear the drill steel and the standard 10 may be moved on its pivot 11 to move it into the vertical position shown in dotted lines in Figure 2 of the drawings and in solid lines in Figure 1. During this pivotal movement the cams 22 ride over the cam surface 23 so as to move the plunger 3 in the cylinder 2 sufficiently to permit the pivotal movement of the carrying standard 10. When the carrying standard 10 reaches its normal vertical or perpendicular position, the cams 22 will have moved off the cam surfaces 23 and the spring 6 will move the plunger 3 inwardly into the cylinder 2 and force the rear edge of the end 9 against the forward end of the cylinder 2 for securely holding the standard 10 in its upright position. The stem 6 is then rotated to move the members 17 and 18 into drill steel guiding position as shown in Figure 1 of the drawings.

It will be understood that the invention is not to be limited to the specific construction or arrangement of parts shown but that they may be widely modified within the invention defined by the claims.

What is claimed is:

1. In a hole spotter for rock drilling machines, an attaching bracket, a cylinder formed on one end of said attaching bracket, a plunger in said cylinder for reciprocatory movement therein, a standard pivotally connected to said plunger, drill steel guiding members carried by said standard, said standard pivotally movable into position perpendicular of the axis of said plunger when in drill steel guiding position and movable

into position parallel to the axis of the plunger when in drill steel non-guiding position, a spring acting on said plunger to hold the standard firmly against said bracket when in drill steel guiding position and to move the pivoted end of the standard into said cylinder when the standard is in non-guiding position, a cam on said standard, and an arcuate surface on said bracket and engaged by said cam for moving the standard and plunger longitudinally of the axis of the cylinder during pivotal movement of the standard.

2. In a hole spotter for rock drilling machines, an attaching bracket, a cylinder formed on one end of said attaching bracket, a plunger in said cylinder for reciprocatory movement therein, a standard pivotally connected to said plunger, drill steel guiding members carried by said standard, said standard pivotally movable into position perpendicular of the axis of said plunger when in drill steel guiding position and movable into position parallel to the axis of the plunger when in drill steel non-guiding position, a spring acting on said plunger to hold the standard firmly against said bracket when in drill steel guiding position and to move the pivoted end of the standard into said cylinder when the standard is in non-guiding position, a cam on said standard, and an arcuate surface on said bracket terminating in a cam receiving depression for receiving said cam when said standard is moved into drill steel non-guiding position.

HERMAN J. SCHORLE.
